FIG. 11

FIGURE 1 is a perspective view of the combined nail clipper and knife with the knife blade and the operating lever in the normally closed position;

FIGURE 2 is a rear end elevational view thereof;

FIGURE 3 is a top plan view thereof;

FIGURE 4 is a front end elevational view thereof;

FIGURE 5 is a side elevational view thereof;

FIGURE 6 is a perspective view of the combined nail clipper and knife with the knife blade extended into cutting position;

FIGURE 7 is a top plan view thereof;

FIGURE 8 is a side elevational view thereof;

FIGURE 9 is a perspective view of the combined nail clipper and knife with the operating lever pivoted into nail-clipping position;

FIGURE 10 is a top plan view thereof; and

FIGURE 11 is a side elevational view thereof.

My design comprises a nail clipper having a slideably mounted knife blade on one face thereof secured in closed position by a lug on the operating lever so that one edge thereof is exposed and pivoted to the narrower end of the casing, said blade having a depending locking lug adjacent the pivot point, all as shown.

I claim:

The ornamental design for a combined nail clipper and knife, as shown and described.
